UNITED STATES PATENT OFFICE.

JUDSON E. WAGONER, OF MONONGAHELA, PENNSYLVANIA, ASSIGNOR TO COMBUSTION ENGINEERING CORPORATION, OF NEW YORK, N. Y., A CORPORATION OF NEW YORK.

STOKER-FURNACE.

1,374,125.

Specification of Letters Patent.

Patented Apr. 5, 1921.

Application filed November 19, 1919. Serial No. 339,118.

To all whom it may concern:

Be it known that I, JUDSON E. WAGONER, a citizen of the United States, residing at Monongahela, county of Washington, State of Pennsylvania, have invented a certain new and useful Improvement in Stoker-Furnaces, of which the following is a full, clear, and exact description.

My invention relates to improvements in stoker furnaces and has for its object to provide a stoker furnace having a movable grate of considerable width fed locally by a means located at one portion thereof and means for distributing the fuel thus supplied transversely along said grate. It further has for its object to provide a furnace having such a pushing means located at a central portion of the furnace and means for distributing the fuel thus supplied in both directions transversely of said grate.

The following is a description of an embodiment of my invention, reference being had to the accompanying drawings, in which—

Figure 1 shows a vertical longitudinal section of a stoker embodying my invention, while

Fig. 2 shows a horizontal section of the same on the line 2—2, Fig. 1.

Referring more particularly to the drawings, 1 and 2 are respectively movable and stationary tubular grate bars of the general type shown in patent to W. R. Wood, No. 818,010 dated April 17, 1906, and constituting the upper section of an inclined stoker grate. 1' and 2' are also respectively movable and stationary tubular grate bars constituting a lower section of the grate. The bars are provided with inlet ports 3, 3' and outlet ports 4, 4' and the bars 1 and 1' are reciprocated by oscillating rocker bars 5, 5' having flanges engaging recesses in the bottoms of the movable bars. The bars are supported by a support 7 and walls 6 and 8, which walls with partitions 9 and 10 form air chambers 11, 12 and 13, 11 being a primary air chamber supplying air to the inlets 3, 12 being a secondary air chamber receiving air from 4 and supplying it to inlet 3' and also to fuel superimposed on the bars 1 and 2, and 13 being a tertiary air chamber receiving air from the outlet ports

4' and supplying it to the fuel on the bars 1', 2'.

The sections above referred to are of considerable width and it is necessary to have fuel evenly distributed thereon from side to side. I accomplish this by my invention by providing a passage 14 leading to a portion of the upper section, preferably the central portion, and of less width than said section, into which passage a hopper 15 discharges. In this passage I arrange a suitable pusher 16 here shown as a reciprocating pusher block which as it reciprocates feeds fuel from the hopper to the upper ends of the inclined grate bars 1 and 2 down which it travels to and over the bars 1' and 2' on account of the movements of the bars 1, 1'. In order to distribute the fuel bed through the passage 14, I provide a double conveyer having two worms 17 and 18, and means for rotating the same clockwise (Fig. 1). One of these conveyers 17 has a right-hand thread and 18 has a left-hand thread so that when rotated clockwise they tend to move fuel from the center in both directions. The conveyer is rotated by a ratchet wheel 19 which is actuated by a pawl 20 carried by a frame 21 embracing the ratchet wheel and swinging on the shaft of the conveyer. This pawl 20 is pivoted at 22 and has a weighted end 23 which tends to hold it in engagement with the ratchet wheel. A detent 24 secured to the frame holds the ratchet wheel from reverse movement. The lower end of the frame 21 is provided with a series of holes to any one of which a link 26 surrounding an eccentric 27 can be connected so as to vary the adjustment and throw of the pawl 20. This eccentric is on a shaft 28, which also carries two other eccentrics 29, 29, actuating links 30, 30, which are connected to lever arms 31 on the rocker bars 5 which lever arms are connected by links 32 to the lever arms 33 on the rocker bars 5', so that as the shaft 28 is revolved the conveyers 17 and 18 are revolved to feed coal and the bars 1, 1' are reciprocated to cause it to move down the grate sections toward the ash pit 34.

In order to reciprocate the pusher block 16, I provide two gears 35, 35 engaging gears on the shaft 28 and provided with crank-

pins 36, 36, which are connected by links 37, 37, with the opposite ends of the block 16 so that as the shafts revolve the pusher block is also reciprocated. In order to protect the 5 ratchet wheel from the fuel, I provide a bridge or housing 38 covering the same and in line with the passage 14, across which the fuel is pushed from the passage to the upper ends of the grate bars of the upper section.

10 As the fuel progresses down the sections it is subjected to currents of air. In the arrangement shown the air flows from the primary chamber 11 through the tubular bars 1 and 2 to chamber 12, whence some of 15 it flows through the upper section to the fuel above, while the balance flows through the tubular bars of the lower section to the chamber 13 and thence to the superimposed fuel. The means for directing the air does 20 not, however, form a part of my invention which consists in the feeding means in conjunction with a moving grate.

25 As will be evident to those skilled in the art, my invention permits of various modifications without departing from the spirit thereof or the scope of the appended claims.

What I claim is:

1. In a stoker furnace, the combination 30 of a series of inclined grate bars arranged adjacent to one another, some of which are movable, a retort adjacent to the upper ends of said bars and transverse to the axes of said bars, a passage located at the central portion of said retort for feeding fuel thereto, a hopper for fuel to be fed, means for feeding fuel from said hopper through said passage to said retort, a double spiral conveyer in the bottom of said retort for distributing fuel fed through said passage 35 to both ends of said retort, and means for actuating said double conveyer.

2. In a stoker furnace, the combination 40 of a series of inclined grate bars arranged adjacent to one another, some of which are movable, a retort adjacent to the upper ends of said bars and transverse to the axes of said bars, a passage located at the central portion of said retort for feeding fuel thereto, a hopper for fuel to be fed, means for feeding fuel through said passage to 45 said retort, a double spiral conveyer in the bottom of said retort for distributing fuel fed through said passage to both ends of said retort, centrally located means for actuating said double conveyer, and a bridge located in the central portion of said retort housing said actuating means.

60 3. In a stoker furnace, the combination of a series of inclined grate bars arranged adjacent to one another, some of which are movable, a retort adjacent to the upper ends of said bars and transverse to the axes of said bars, a passage located at the central portion of said retort for feeding fuel thereto, a hopper for fuel to be fed, feed-

70 ing means for moving fuel through said passage to said retort, a double spiral conveyer in the bottom of said retort for distributing fuel fed through said passage to both ends of said retort, means for actuating said double conveyer, said actuating means consisting of a ratchet wheel located at the central portion of said double conveyer, an oscillating pawl for actuating said ratchet wheel, a bridge located in the central portion of said retort and housing said ratchet wheel and a shaft for operating said feeding means and means operatively connected thereto for actuating said pawl.

75 4. In a stoker furnace, the combination of a series of inclined grate bars arranged adjacent to one another, some of which are movable, a retort adjacent to the upper ends of said bars and transverse to the axes of said bars, a passage located at the central portion of said retort for feeding fuel thereto, a hopper for fuel to be fed, feeding means for moving fuel through said passage to said retort, a double spiral conveyer in the bottom of said retort for distributing fuel fed through said passage to 80 both ends of said retort, means for actuating said double conveyer, a shaft and operative connections for operating said feeding means, and an eccentric actuated thereby for reciprocating said movable bars.

90 5. In a stoker furnace, the combination 95 of a series of inclined grate bars arranged adjacent to one another, some of which are movable, a retort adjacent to the upper ends of said bars and transverse to the axes of said bars, a passage located at the central portion of said retort for feeding fuel thereto, a hopper for fuel to be fed, feeding means for moving fuel through said passage to said retort, a double spiral conveyer in the bottom of said retort for distributing fuel fed through said passage to 100 both ends of said retort, means for actuating said double conveyer, said actuating means consisting of a ratchet wheel located at the central portion of said double conveyer, an oscillating pawl for actuating said ratchet wheel, a bridge located in the central portion of said retort and housing said ratchet wheel, and a shaft and operative connections for operating said feeding means, an eccentric connected therewith for reciprocating said movable bars, and an eccentric also connected thereto for actuating said pawl.

105 6. In a stoker furnace, the combination 125 of a series of inclined grate bars arranged adjacent to one another, some of which are movable, a retort adjacent to the upper ends of said bars and transverse to the axes of said bars, a passage located at the central portion of said retort for feeding fuel thereto, a hopper for fuel to be fed, feed-

ing means for moving fuel through said passage to said retort, a double spiral conveyer in the bottom of said retort for distributing fuel fed through said passage to both ends of said retort, means for actuating said double conveyer, a shaft and operative connections for operating said feeding

means, an eccentric actuated thereby for reciprocating said movable bars, a second series of grate bars extending beyond and receiving fuel from the first series, and means actuated by said eccentric for actuating the movable bars of said second series. 10

JUDSON E. WAGONER.
